VENDING MACHINE

William J. Smith, San Jose, Calif., assignor to S & S Vending Machine Co., San Jose, Calif., a corporation of California

Filed Jan. 27, 1958, Ser. No. 711,243

4 Claims. (Cl. 312—35)

This invention is directed to, and it is a major object to provide, a novel machine for vending a product—such as milk in a carton—from within a cabinet to a customer standing outside the latter.

Another important object of the invention is to provide a vending machine which embodies—in combination, and within the cabinet—a carton receiving and delivery rotor manually actuated by the purchaser, and an electric motor driven pusher unit adapted to feed cartons one at a time from a storage platform into the receiving and delivery rotor.

The front or carton feed-off end of the storage platform lies above the rotor and the latter has a normally upwardly opening pocket therein for reception of each carton as it is fed off said end of the platform and falls downwardly therefrom; an additional object of the invention being to provide the rotor, within the same, with a novel decelerating device which absorbs the shock of, or cushions the fall of, the carton into said pocket, whereby to prevent rupturing of the carton and escape of the contents.

Another object of the invention is to provide a carton receiving and delivery rotor which is constructed for ease of manual operation; for gravitational return to a carton receiving position after each delivery; for the prevention of unauthorized access to the carton storage platform from exteriorly of the machine and through the rotor; and for drainage of any moisture which may accumulate in the bottom of the pocket in said rotor.

The carton storage platform is adapted to support a plurality of transverse rows of cartons in longitudinally guided courses, and a further object of the invention is to provide the pusher unit with a transversely stepped front or carton engaging face having each step corresponding to, and longitudinally aligned with, a related course of the cartons, whereby with a predetermined advance of the pusher unit only a single carton is fed off the front end of said platform to fall into the rotor.

A still further object of the invention is to provide an electric motor driven pusher unit, for the purpose described, of novel construction and mounting, including the securing of the drive motor in the unit for travel therewith, and a rack and pinion mechanism responsive to the motor operative to advance said pusher unit along the carton storage platform.

It is also an object of the invention to provide a vending machine which is designed for ready and economical manufacture, and long, continued, and effective service with a minimum of maintenance or repair being required.

Still another object is to provide a practical and reliable vending machine, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the vending machine as mounted in a refrigerated cabinet; the latter being in section.

Fig. 2 is an elevation of the front of the machine; i.e., that portion exposed to the outside of the cabinet.

Fig. 3 is a top plan view of the machine showing particularly the carton storage rack and the electric motor driven pusher unit; the refrigerated cabinet again being in section.

Fig. 4 is a fragmentary enlarged sectional view, taken substantially on line 4—4 of Fig. 7, showing primarily the rotor, its mount, and the manually operated rotor actuating device.

Fig. 5 is an enlarged end view of the rotor showing the rotor actuating device in detail.

Fig. 6 is an enlarged front elevation, partly broken away, of the pusher unit; the carton storage platform being in section.

Fig. 7 is an enlarged fragmentary elevation, mainly in section, showing the rotor in its initial or carton receiving position, and as disposed below the feed-off end of the carton storage platform.

Fig. 8 is a similar sectional elevation of the rotor 15 in the same position as shown in Fig. 7, but after a carton has been fed into the pocket.

Fig. 9 is likewise a similar view, but shows the rotor as part-rotated to carton access and delivery position.

Referring now more particularly to the drawings, and to the characters of reference marked thereon, the vending machine is mounted in an insulated and suitably refrigerated cabinet, indicated generally at 1, which cabinet may be supported—at proper elevation—by legs 2; the cabinet including a front wall 3, a rear wall 4, and—at one side—an access door 5 normally maintained closed by a locked hasp 6. The door 5, when open, permits of access into the cabinet 1 for the purpose of loading the vending machine, servicing it, or the like.

The front wall 3 is initially formed with a rectangular opening 7, which opening is closed by the front portion of the vending machine; the latter comprising the following:

A rectangular mounting frame 8 is secured in—and extends about—the rectangular opening 7, and such mounting frame 8 supports an upper transversely extending insulated panel 9 and a lower transversely extending insulated filler 10. Such panel 9 and filler 10 are spaced apart vertically to leave an access opening 11 therebetween and extend from the left hand end of mounting frame 8 toward, but terminate short of, the opposite end, as shown in Fig. 2; such frame at said opposite end being formed with a box-like recess R on the rear of which is mounted the coin reception slot 12 for a coin controlled energizing circuit for the machine, but which circuit forms no part of the present invention.

The rectangular mounting frame 8 supports—in fixed relation at the ends of the upper panel 9 and filler 10—rigid end plates 13 disposed in facing relation and projecting rearwardly into the cabinet 1. The forward portion 14 of the end plate adjacent the recess R defines the corresponding side of said recess for a purpose which will hereinafter appear.

A cylindrical rotor 15 is disposed horizontally and extends between the end plates 13, being axially journaled at the adjacent ends in connection with said end plates, as at 16, whereby said rotor is turnable about a horizontal transverse axis.

The rotor 15, which terminates at its ends adjacent but short of the corresponding end plates 13, is formed internally with a full-length, substantially diametral, carton receiving pocket 17 which—in the initial or carton receiving position of said rotor—opens at the top, or

upwardly; the top opening of the pocket being indicated at 18.

The pocket 17 is defined, within the rotor 15, by a front wall 19, a rear wall 20, and a bottom plate 21. The bottom plate 21 is disposed so that any moisture which collects on it drains toward—and discharges from—one end of the rotor 15 onto the floor of the cabinet 1, whence such moisture can be readily mopped up by the attendant.

The portion of the rotor 15 which is to the rear of the access and delivery opening 11 when said rotor is in its initial or carton receiving position is insulated, as at 22, and the rear portion of the insulated upper panel 9 is provided with a concave 23 disposed in close symmetrical relation to the rotor 15.

In a plane above the rotor 15 the machine includes—within the refrigerated cabinet 1—a carton storage platform, indicated generally at 24, which is comprised of a plurality of side by side guideways 25, each defined by a plurality of longitudinally extending, transversely spaced rods 26 of relatively small diameter, and—at the sides of each guideway—longitudinally extending rods 27 of larger diameter (see Figs. 3 and 6).

The rods 26 and 27 are secured to and supported by—
at longitudinally spaced points—crossbars, one of which is indicated at 28. The cross bars 28 are in turn secured to longitudinal side bars 29 attached at the rear end to the rear wall 4, and attached at the front end to the upper panel 9.

The carton supporting platform 24—except for the side bars 29—terminates some distance short of the upper panel 9, and in a vertical transverse plane substantially aligned with the rear edge of the top opening 18 of the pocket 17 in the rotor 15 when the latter is in its initial or carton receiving position, as shown in Fig. 7. This forms a throat 30 ahead of—and extending downwardly from—the front end of the carton storage platform 24, with such throat in register with said top opening 18.

A transversely extending, substantially full-width, carton pusher unit 31 rests on and spans the carton storage platform 24; such pusher unit 31 including a front 32, a top 33, a back 34, and ends 35 and 36.

The front 32 of the pusher unit 31 is transversely stepped, as shown, with each stepped portion corresponding to, and being aligned with, one of the guideways 25; the purpose of such transverse stepping to be hereinafter described.

The pusher unit 31 is retained on, and adapted to be driven along, the carton storage platform 24, as follows:

A cross shaft 37 disposed relatively close to the bottom of said pusher unit extends within the same from side to side, projects through the ends 35 and 36, and thence extends a short distance therebeyond; the outer ends of said cross shaft 37 being formed as trunnions 38 which are engaged between the adjacent side bar 29 and a laterally inwardly projecting or overhanging flange 39 included in longitudinal channels 40 which extend along opposite sides of said carton storage platform 24.

The side bars 29 also support—in fixed relation—upwardly facing, longitudinal racks 41, and driven pinions 42 engage and run on said racks 41. The pinions 42, which are fixed on the cross shaft 37 are driven as follows:

A reversible electric motor 43 is disposed within the pusher 31, being mounted on the end 35 thereof, as shown in Fig. 6; such electric motor 43 including a reduction gear head 44, and a laterally outwardly projecting drive shaft 45 which extends through said end 35. At its outer end the drive shaft 45 is fitted with a pinion 46 which engages in driving relation with the adjacent pinion 42 on said cross shaft 37.

With energization of the electric motor 43 and its operation in one direction, the above arrangement results in both of the pinions 42 being driven, with said

pinions then traveling forwardly on the racks 41 to advance the pusher unit 31.

The electric motor 43 is placed in operation by the aforementioned coin controlled energizing circuit, and which circuit is responsive to a coin (or coins) being deposited in the slot 12 in the back of the recess R, and which of course is accessible to a purchaser standing in front of the cabinet 1.

A flexible electric cord 47 leads into the pusher unit 31 through the end 36 to supply current to the reversible electric motor 43, and within which pusher unit 31 a part of the controlled energizing circuit is disposed.

A manual push button switch 48 and a snap-action or toggle switch 49—mounted on said end 36, and accessible to the attendant from within the cabinet 1—are operative to cause forward and rearward travel, respectively, of said pusher unit 31. Of course, the switches 48 and 49 are used by the attendant solely during loading of the machine.

Immediately below the forward or discharge end of the carton storage platform 24, there is a full-width cross shaft 50 suitably journaled adjacent its ends, and provided between such ends with a full-width, normally forwardly projecting, trigger plate 51 which extends into the throat 30, as shown in Fig. 7. At one end the cross shaft 50 projects through the adjacent end plate 13, and beyond the latter is formed with a radial finger 52 which carries a counterweight 53 which normally rests downwardly against a stop 54; the counterweight then engaging a switch 55 mounted on said end plate 13 (see Figs. 1 and 3).

The rotor 15 is provided—internally thereof—with a carton decelerating device, indicated generally at 56; such device being operative to cushion the fall—into the rotor—of a carton fed from the platform 24, in the manner as will hereinafter appear.

The carton decelerating device 56 comprises a normally horizontal, full-width catch plate 57 disposed in the pocket 17 lengthwise thereof and normally adjacent the top opening 18. The catch plate 57 is mounted in connection with, and normally maintained in its raised position by, a pair of spaced arms 58 fixed in connection with, and radiating from, a cross shaft 59 journaled in connection with, and spanning between, the ends 60 of the rotor at the normally back side thereof.

The radial arms 58 extend, from the cross shaft 59, in normally upwardly and forwardly inclined relation, passing through corresponding slots 61 in the rear wall 20, and thence being attached to the catch plate 57; the slots from their upper inception extending substantially to the bottom of said rear wall 20, whereby to permit of downward swinging of the catch plate 57 from its initial raised position, as in Fig. 7, to a lowered position, as in Fig. 8.

Lowering of the catch plate 57 is yieldably resisted by adjustable torque spring units 62 connected between each end portion of the cross shaft 59 and the adjacent rotor end 60.

The rotor 15 is adapted to be manually part-rotated from its normal carton receiving position, as shown in Fig. 7, to a carton access and delivery position in register with the opening 11, as shown in Fig. 9, by means of the following rotor actuating device:

The forward portion 14 of the end plate 13 which forms one side of the recess R has a vertical slot 63 therein, and a vertical slide 64 is disposed immediately laterally inwardly of such slot for up and down travel; there being a hand knob 65 fixed to said slide 64 and projecting through the slot 63 into the recess R for grasping by a purchaser standing in front of the machine.

At its lower end the vertical slide 64 includes a rearwardly projecting, flat, vertically disposed fork 66 which straddles a flanged roller 67 secured—as at 68—

to the adjacent end 60 of the rotor in offset relation to the axis of the latter.

Upon a purchaser grasping the knob 65 and pressing downwardly, the fork 66, working through the flanged roller 67, part-turns the rotor 15 from its carton receiving position to its access and carton delivery position.

The arcuate extent of the concave 23 is such that the top opening 18 of the pocket 17 is full-closed by said concave before such opening 18 begins to register with the opening 11; this being of advantage in that it prevents the introduction of a tampering instrumentality into the machine from said opening 11.

When the above described vending machine is in use, a multiplicity of the cartons C are placed on the storage platform 24, with a longitudinal course of such cartons in each guideway 25, and with the corresponding cartons of the courses in transverse rows.

The cartons in each transverse row are staggered—relative to each other, and lengthwise of the platform 24—a distance equal to the depth of the corresponding steps on the front 32 of the pusher unit 31; such stepped front 32 of the pusher unit engaging against the rear-most row of cartons.

Such pusher unit 31, when the storage platform 24 is fully loaded, occupies a retracted position, as shown in broken lines in Fig. 1; the unit progressing forwardly with successive dispensing operations, and—as shown in Fig. 1 in full lines—the unit is disposed at an advanced position, with only a limited number of cartons remaining to be dispensed.

Each time that the electric motor 43 is energized in a direction to move the pusher unit 31 forwardly, and which occurs in response to a deposit of a coin (or coins) in the slot 12, one carton escapes the front end of the platform 24 and falls downwardly therefrom; this result being accomplished more specifically as follows:

With forward movements of the pusher unit 31—and at which time all cartons on the platform are advanced, the individual cartons progressively reach the front end of the platform 24 and are moved successively (by reason of their staggered relation in each row) partly off of said end and tilt forward at the top against the rear face 69 of the front wall 3, yet while remaining supported at the bottom by said front end of the platform.

As it requires further relatively short forward movements of the push unit 31 to fully push each tilted carton off the front end of the platform 24, a number of such cartons are tilted at all times against the front wall, except when only one carton remains to be dispensed.

In Fig. 3 there is illustrated—for example—three cartons in tilted position; i.e., the remaining one from the second from the last row, and two from the next to the last row.

With one or more cartons in tilted position, with differential extent of bottom engagement on the front end of the platform 24, each subsequent forward movement of the pusher unit 31 causes the tilted carton having the least bottom engaged with said front end of the platform to be pushed entirely off the latter, whence said carton falls downwardly through the throat 30; all remaining cartons on the platform being progressed one step.

Of course, when the machine is initially loaded, the pusher unit is run forward manually by the attendant to cause one or more of the cartons to assume a tilted position with at least one of said tilted cartons far enough advanced at the bottom so that upon the first operation of the machine said one carton will dispense.

As each carton is dispensed—i.e. falls off of the forward end of the platform 24 and drops downwardly

through the throat 30—such carton engages and lowers the trigger plate 51, which results in operation of switch 55; the latter being included in the motor energizing circuit in any suitable manner to open the same and stop the pusher unit 31. By the time said pusher unit is stopped it has moved another tilted carton to position for discharge upon occurrence of the next following operation of the machine.

Each carton C, as fed off the front end of the platform 24, is received—as it drops—in the normally upwardly opening pocket 17 of the rotor 15; the fall or drop of such carton being greatly decelerated or cushioned to prevent any damage to the carton by means of the hereinbefore described device 56. Thus, as a carton C falls into the pocket 17 it is received on the catch plate 57, whose lowering is yieldably resisted by the adjustable torque spring units 62; such spring units 62 being set so that while they cushion the fall of the carton, its weight will depress the catch plate 57 to the bottom of the pocket, in the manner shown in Fig. 8, and at which time the carton is wholly within said pocket 17.

Nextly, the purchaser—from exteriorly of the cabinet 1—grasps the knob 65 and pushes it downwardly to its limit of movement, part-turning the rotor 15 until the pocket opening 18 is in register with the opening 11. Thereafter, the purchaser merely reaches through said registering openings and withdraws the carton (see Fig. 9).

As will be obvious, the catch plate 57 will then exert a pressure against the bottom of the carton, tending to slide the same out of the pocket. In order to prevent this pressure from being effective until the purchaser is ready to withdraw the carton, a rigid lip 70 extends part way across the pocket opening 18 from the wall 19, leaving a space between the lip and the opposite wall 20 of sufficient width to freely receive a carton therethrough; said walls diverging upwardly relative to each other so that the width of the pocket at the bottom is not materially greater than the width of a carton, as clearly shown in Fig. 8. Thus, when a carton is to be withdrawn from the pocket, it must first be lifted at its outer end sufficiently to clear the lip 70 before the urging pressure of plate 57 can be effective in aiding the withdrawal of the carton. By this arrangement there is no danger that the carton will be ejected from the pocket and catch the purchaser unawares.

After the carton is so withdrawn by the purchaser and the knob 65 released, the rotor 15 returns by gravity to its initial or starting position, with the pocket opening 18 uppermost; this being accomplished by counter-weighting the rotor, as at 71.

In order to prevent actuation of the machine after the last carton is dispensed, the pusher unit 31 is provided—at the front—with triggers 72 normally depressed by the cartons which said triggers engage. However, when the engaged cartons have been dispensed, said triggers operate switches (not shown) within the pusher unit 31, and which switches are operative in any suitable manner to open the motor energizing circuit. Such switches—together with the other switches hereinbefore described, and the coin controlled energizing circuit generally—form no part, as previously indicated, of the present invention, as sundry electrical circuits can be employed for the purpose.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is

claimed as new and useful, and upon which Letters Patent are desired:

1. In an article vending machine which includes an enclosing cabinet having a wall provided with an access opening, a horizontal-axis rotor forming a closure for said access opening, means forming a pocket in the rotor open at one end to the periphery thereof, the rotor being normally disposed with the pocket-opening at the top and out of register with the access opening and into which pocket an article to be vended is then received from the machine, means journaling the rotor for turning to a position with the pocket opening in register with the access opening, means to so turn the rotor, said pocket forming means comprising walls extending chordally of the periphery of the rotor, and a lip projecting transversely of the pocket in overhanging relation to the pocket opening from the wall thereof which is on the side of the rotor nearest said cabinet wall and disposed at the open end of the pocket; said lip terminating from the opposite wall a distance greater than the width of the article; the access opening being disposed so that when the pocket opening is in register therewith, said first named pocket wall will be disposed at a downward slope toward the access opening; and a shock absorbing device for the article as received in the pocket mounted in the rotor and including an article-engaging plate tending to urge the article out of the pocket subsequent to a shock absorbing action and when the rotor is turned so that the pocket opening is in register with the access opening.

2. In an article vending machine which includes an enclosing cabinet having a wall provided with an access opening, a horizontal-axis rotor forming a closure for said access opening, means forming a pocket in the rotor open at one end to the periphery thereof, the rotor being normally disposed with the pocket-opening at the top and out of register with the access opening and into which pocket an article to be vended is then received from the machine, means journaling the rotor for turning to a

position with the pocket opening in register with the access opening, means to do turn the rotor, and a shock absorbing device for the article as received in the pocket mounted in the rotor and including an article-engaging plate tending to urge the article out of the pocket subsequent to a shock absorbing action and when the rotor is turned so that the pocket opening is in register with the access opening.

5 3. A structure, as in claim 2, with means provided with the pocket preventing such urging pressure from being effective until the article in the pocket is engaged and initially manually lifted at its outer end.

10 4. A structure, as in claim 2, in which the pocket forming means comprises opposed walls, and means provided with the pocket preventing such urging pressure from being effective until the article in the pocket is engaged and initially manually lifted at its outer end; said last named means comprising a lip projecting transversely in 15 overhanging relation to the pocket opening from the wall thereof which is on the side of the rotor nearest the cabinet wall and disposed adjacent the pocket opening so that when the rotor is turned to align the pocket opening with the access opening an article in the pocket will rest on said pocket wall and the lip will project upwardly to 20 form a stop for the adjacent end of the article.
